UNITED STATES PATENT OFFICE.

ROBERT F. TIMMONS, OF COSHOCOTON, OHIO.

LICENSE-TAG.

1,267,015.

Specification of Letters Patent. Patented May 21, 1918.

Application filed April 14, 1917. Serial No. 162,155.

To all whom it may concern:

Be it known that I, ROBERT F. TIMMONS, a citizen of the United States, residing at Coshocoton, in the county of Coshocoton and State of Ohio, have invented certain new and useful Improvements in License-Tags, of which the following is a specification.

This invention relates to license tags for automobiles, motorcycles and other vehicles upon which the law requires annual license fees to be paid and tags to be displayed indicating the payment of such fees and carrying permission to use the roads of a State. The primary object of the invention is to provide a license tag which may be used indefinitely and which will be capable of receiving an insert indicating that the license fee for the current year has been paid. Other incidental objects will appear as the description of the same proceeds.

In the accompanying drawings:

Figure 1 is an elevation of a license tag embodying my invention;

Fig. 2 is a longitudinal section on the line 2—2 of Fig. 1;

Fig. 3 is an elevation of a portion of a tag showing a different construction;

Fig. 4 is a transverse section on the line 4—4 of Fig. 3;

Fig. 5 is a detail section on the line 5—5 of Fig. 3.

The license tag will consist of a plate 1 of metal or other durable material of the form and dimensions now generally employed. This plate will be provided with openings 2 at or near its corners for the reception of permanent fastening devices whereby it may be rigidly secured to the vehicle when the regulations require such permanent fastening. It will also be provided at its upper edge with one or more slots 3 through which attaching straps may be passed when the regulations of any particular State or other division of government permits the use of such means of applying the tag. Upon the face of the plate 1 will be displayed a number indicated at 4, which will be the registry number of the vehicle to which the tag is applied and it is the object of my invention to permit a vehicle to retain a certain number permanently so that the plate 1 need not be changed from year to year. Near one end of the main plate 1, I provide guides or ways 5 to re-

ceive an insert 6 upon which may be displayed, as at 7, the number of the current license year and also letters or other indicia, as at 8, to denote the name of the State issuing the license. The insert 6 may be constructed with a longitudinal slot 9 corresponding in form and dimensions to the slot 3 in the plate 1 and so located as to register with one of said slots 3 when the insert is in position. Obviously, the attaching strap will then serve also to secure and prevent loss of the insert. The insert will also be provided with openings 20 adapted to register with openings 2 in the back plate so that when permanent fastenings are employed the insert will be firmly secured by the same devices. The guides or ways 5 may conveniently be in the form of lips struck up from the main plate and bent over, as shown most clearly in Fig. 2, so as to provide spaces which may receive the edges of the insert and near the lower edge of the main plate similar lips 10 are struck up therefrom to be engaged by and form rests for the lower edge of the insert so that the insert will be firmly supported and cutting or wearing strain upon the attaching strap, when such strap is used, will be avoided.

In Figs. 3, 4 and 5, I have shown a form of the invention in which the plate 11 corresponds in all respects to the plate 1 previously described. Lips or guides 12 are struck up from this plate to receive and support the insert 13 and right angular lips or sockets 14 are also struck up from the plate 11 to receive and extend over the lower corners of the insert so as to protect the same and prevent the bending or breaking thereof. Near the upper edge of the plate 11, a stop 15 is struck up therefrom to engage the upper edge of the insert and thereby retain the same in place so that the attaching strap passed through the slot 16 in the plate 11 will not be subjected to wear from the insert. It will be readily understood that as the insert will generally be formed of sheet metal, it may be readily sprung over the stop or retaining lip 15 so as to clear the same and engage below it.

It is thought to be evident from the foregoing description, taken in connection with the accompanying drawings, that my invention provides a license tag which may be used indefinitely and upon which the dis-

play surface may be changed from year to year quickly and easily. The owner of the vehicle will thus be saved the expense of paying for a large tag every year and will 5 also avoid the trouble and labor of attaching the same to a vehicle, while the governmental authority issuing the license will likewise be enabled to effect a considerable saving in the purchase of tags. The insert may 10 be slipped into place without removing the tag from the vehicle and in order to distinguish the insert of one year easily from the insert representing another year the face thereof may be coated with different 15 colors from year to year so that even if the numeral indicating the current year should be obliterated the color of the insert would indicate for what year it was issued.

Having thus described the invention, what is claimed as new is:

A license tag comprising a main plate, a supplemental plate designed for disposal against the face of the main plate, and means upon the main plate for supporting the supplemental plate against downward movement and for holding the same against lateral movement, the said plates having openings designed to register when the plates are assembled whereby to provide means for the passage of an element for attaching the tag to a vehicle and also for holding the supplemental plate against upward displacement. 20 25 30

In testimony whereof I affix my signature.

ROBERT F. TIMMONS. [L.S.]
